UNITED STATES PATENT OFFICE.

LEMUEL A. LITTLEFIELD, OF ROCKFORD, ILLINOIS, ASSIGNOR TO ROCKFORD SILVER PLATE COMPANY, OF ROCKFORD, ILLINOIS, A CORPORATION OF ILLINOIS.

DESIGN FOR A HANDLE FOR SPOONS, FORKS, OR SIMILAR ARTICLES.

43,823.

Specification for Design.

Patented Apr. 8, 1913.

Application filed November 19, 1912. Serial No. 732,371. Term of patent 7 years.

To all whom it may concern:

Be it known that I, LEMUEL A. LITTLEFIELD, a citizen of the United States, residing at Rockford, in the county of Winnebago and State of Illinois, have invented a new, original, and ornamental Design for Handles for Spoons, Forks, or Similar Articles, of which the following is a specification, reference being had to the accompanying drawing, forming part thereof.

Figure 1 is a plan view of a spoon or

fork, showing my new design. Fig. 2 is a cross-sectional perspective view of the end of the handle of the spoon or fork, taken on the line 2—2 of Fig. 1.

I claim:

The ornamental design for a handle for spoons, forks, or similar articles, as shown.

LEMUEL A. LITTLEFIELD.
